TRUCK

Fred E. Bachman, Chicago, Ill., assignor to American Steel Foundries, Chicago, Ill., a corporation of New Jersey

Application June 12, 1931, Serial No. 543,763

32 Claims. (CL. 185—197.1)

This invention pertains to car trucks.

It is an object of this invention to provide improved and economical trucks wherein loads are supported by springs of different character.

5 Another object is to provide a truck construction wherein coil and elliptic springs are used to simultaneously support loads and wherein spring capacity is greatly increased over similar types of trucks.

10 A further object is to provide a truck construction wherein a movable bolster is used supported by coil and elliptic springs on adjacent frame structure.

15 With these and various other objects in view, the invention may consist of certain novel features of construction and operation, as will be more fully described and particularly pointed out in the specification, drawings and claims appended hereto.

20 In the drawings, which illustrate an embodiment of the device and wherein like reference characters are used to designate like parts—

Figure 1 is a fragmentary sectional top plan view of a truck construction embodying the invention;

25 Figure 2 is a side elevation partly in section of the truck construction shown in Figure 1, the section being taken substantially at the longitudinal center line of the truck;

30 Figure 3 is an end elevation partly in section of the truck construction shown in Figure 1, the section thereof being taken substantially on the transverse center line of the truck;

35 Figure 4 is a fragmentary sectional top plan view of a truck construction embodying a modified form of the invention;

40 Figure 5 is a side elevation partly in section of the truck construction shown in Figure 4, the section being taken substantially at the longitudinal center line of the truck;

45 Figure 6 is an end elevation partly in section of the truck construction shown in Figure 4, the section thereof being taken substantially at the transverse center line of the truck;

Figure 7 is a side elevation of another modified form of truck;

50 Figure 8 is an end elevation partly in section of the truck construction shown in Figure 7, the section being taken substantially at the transverse center line of the truck;

Figure 9 is still another modified form of the truck construction;

55 Figure 10 is an end elevation partly in section of the truck construction shown in Figure 9, the

section thereof being taken substantially at the transverse center line of the truck;

Figure 11 is a side elevation of yet another modified form of the truck construction;

5 Figure 12 is an end elevation partly in section of the truck shown in Figure 11, the section thereof being taken substantially at the transverse center line of the truck;

Figure 13 is a side elevation of another modified form of the truck construction;

10 Figure 14 is an end elevation partly in section of the truck construction shown in Figure 13, the section thereof being taken substantially at the transverse center line of the truck.

15 Referring first of all more particularly to the construction shown in Figures 1 to 3 inclusive, the truck side frame 10 comprises a tension member 12 and a spaced compression member 14, said members merging into each other at 16 adjacent the integral or removable journal box 18. The 20 journal box is of any type, such as the A. R. A. type of journal box, and accommodates the end of the axle 20 of the wheel and axle assembly 22, which may be of any type, such as the friction or the Simplex. The side frame is extended beyond the ends of the wheels, providing a brake hanger bracket 24, and the tension and compression members are integrally connected by means of the vertically extending column guides 25, said column guides being spaced apart to form a window. 25

30 The transverse bolster 26 is provided, the ends of which are spaced from the side frame and are provided with stops 28 which, in extreme transverse swinging movement, are limited in this 35 movement by the adjacent portions 30 of the transom 32. The transom 32 is provided with spaced supporting members 34 integrally connected at their ends by the transverse connecting members 36, said members being provided 40 with the stop portions 30, supra, and having column guide cooperating portions 38 embracing the column guides 25 for sliding movement with respect thereto. The bolster 26, which as shown 45 is provided with the integral center bearing 40, is also provided with a depending hanger seat 42 disposed adjacent the ends of the bolster and braced by means of the bracket 44, the seat being adapted to receive the swing hanger saddle 46. The ends of said saddle 46 are supportably engaged with the hanger links 48, the hanger links 50 extending within, and being pivotally connected to, the spaced members 34 by means of the pin 50, said pin being locked in its socket by means of the bolt 52 passing through the spaced ears 54. 55

55

The bolster is of the self-centering type, the links 48 sloping outwardly and downwardly whereby the tendency is to always return the bolsters to normal or center position.

5 The connecting member 36 of the spaced members 34 is provided adjacent its center with depending coil spring seats 56 adapted to seat upon the coil springs 58 seated on suitable seat portions 60 of the tension member 12, the coil 10 springs being disposed between leaf springs 62, also seated on the tension member between the column guides, the leaf springs seating in a suitable seat 64 provided in the integral connecting member 36, said seats being disposed adjacent 15 the column guides. The truck frames are connected by means of the spring plank 66 rigidly secured to the bracket 68 provided on the truck frame adjacent the spring seat 60.

In the truck construction shown in Figures 4 to 20 6 inclusive, the truck side frame 70 is provided with the tension and compression members 72 and 74 merging adjacent their ends and being provided with a journal box 76. The journal boxes accommodate the ends of the axle 78 of 25 the wheel and axle assembly 80, which may be of any desired type such as the friction or the Simplex. The tension and compression members of the side frame are integrally connected by the spaced column guides 82 forming a window. The side frames are connected by means 30 of the transversely extending spring plank 84 extending within said window, the spring plank being upwardly flanged as at 86 providing embracing portions for the spring seats 88. The 35 spring seats 88 are provided with spaced coil springs 90 disposed adjacent the column guides, the opposite ends of the coil springs being seated in cooperating seats 92 in the spring cap member 94. 40 Leaf springs 96 adjacently disposed are seated in the spring seat 88 and also in a corresponding seat 98 provided in the spring cap member 94. The spring cap member 94 is provided with anti-friction bearing seats 100 accommodating 45 the anti-friction rollers 102. The transverse bolster 104, provided with the integral center bearing 106, extends through the window and is provided with anti-friction bearing seats 108 seating on the anti-friction rollers 102. The 50 spring cap members 94 are provided with spaced members 110 embracing the column guides for guiding cooperation therewith. The ends of the bolster are provided with stop members 112 permitting limited transverse movements of the bolsters with respect to the column guides and side 55 frame. The anti-friction bearings also serve to limit this movement and to return the bolster to center position.

In the truck construction shown in Figures 60 7 and 8, the side frame 128 is provided with the tension and compression members 122 and 124 merging adjacent their ends, being provided with the journal boxes 126. The journal boxes accommodate the ends of the axle 128 of the wheel 65 and axle assembly 130 which may be of any desired type, such as the friction or Simplex. The tension and compression members of the side frame are integrally connected by the spaced column guides 132 forming a window in the side frames. The side frames are connected by means 70 of the transversely extending spring plank 134 extending within said window, the spring plank being preferably upwardly flanged as at 136.

The bolster 138 extends within the windows 75 and is provided with guide portions 140 co-oper-

ating with the column guides 132. The tension member 122 is provided with raised coil spring seats 142 and the bolster is provided with coil spring seats 144 between which the coil springs 146 are disposed. The bolster is provided with a 5 leaf spring seat 148 disposed inwardly of the side frames and accommodating the leaf or semi-elliptic springs 150. The semi-elliptic springs are spaced between the coil springs 146 and the outer ends thereof are provided with suitable shoes 10 152 supported on the spring plank 136 directly within the window of the side frame. The opposite end of the leaf springs is provided with a suitable shoe 154 pivoted as at 156 to the link 158, the opposite end of the link being pivoted 15 as at 160 to the bolster.

In the construction shown in Figures 9 and 10 the side frame 160 is provided with the tension and compression members 162 and 164 merging adjacent their ends and provided with the journal boxes 166. The tension and compression members are connected by means of the column guides 168 forming a window, the bottom chord thereof being substantially on one level. The journal boxes accommodate the ends of the axle 25 170 of the wheel and axle assembly 172, and the side frames are connected by the spring plank 174 preferably flanged as at 176. The bolster 178 extends within the side frame, being provided with guides 180 cooperating with the column guides 168. 30

Within the opening formed in the side frame there is provided an anti-friction bearing seat 182 fixed with respect to the side frame. A movable seat 184 is provided, spaced by means of the anti-friction rollers 186. The member 184 provides spaced coil spring seats 188 adjacent the column guides adapted to accommodate the coil springs 190, the other end of the coil springs seating in coil spring seats 192 provided in the end of the 40 bolster. The bolster is provided with spaced leaf spring seats 194 provided therein and spaced between the side frames for accommodating the leaf or semi-elliptic springs 196. The outer end of the springs is provided with a shoe 198 disposed in seat 200 provided in the member 184, the opposite ends of the leaf springs being provided with a suitable shoe 202 disposed in a seat 204 provided in the bolster. 45

The invention disclosed and described above 50 and as illustrated in Figures 7 to 10 inclusive, are described and claimed in application Serial No. 738,674, filed August 6, 1934, which application is a continuation-in-part of this application.

Referring now to the construction illustrated 55 in Figures 11 and 12, the truck side frame 228 is of the usual truss construction provided with the journal boxes 222 cooperating with the journals of the wheel and axle assembly 224. The side frame includes the compression member 226 and 60 the tension member 228 merging into each other adjacent the journal boxes and integrally connected by means of the spaced column guides 230 forming a side frame opening 232. The bolster 234 provided with the main bearing 236 65 extends into the opening 232 and is provided with columns 238 cooperating with the column guides. The bolster is provided with a depending spring seat 240 adjacent the center thereof adapted to be supported on the leaf spring assembly 242, 70 the ends of which are supported on the seats 244 provided on the tension member 228, a suitable opening being provided in the column guides and tension members for the reception of the end of the springs and to permit ready assembly as by 75

insertion of the leaf spring through the top or bottom chord of the tension member in accordance with well known practice. The bolster is additionally supported by the nests of coil springs 5 disposed on the spring plank 248 connecting the spaced side frames.

In the construction illustrated in Figures 13 and 14, the side frame 280 is also of the usual truss construction provided with the journal boxes 282 cooperating with the journals of the wheel and axle assembly 284. The truck frame 280 includes the tension member 286 and the compression member 288 merging adjacent the journal boxes and connected by the spaced columns 15 289 provided with the column guides 290 forming the opening 292. The bolster 294 is provided with the center bearing 296 and extends into the opening, and is provided with columns 298 cooperating with the column guides; the bolster in this 20 case is supported on the spring plank 300 by means of the nests of coil springs 302, the spring plank serving to connect the side frames, it being seen that the coil springs are disposed on the plurality of levels though they may be supported 25 on one level. The compression member is provided adjacent the journal boxes with the opening 304 through which leaf springs 306 may be inserted, the leaf springs 306 serving to support the bolster adjacent the center thereof, the ends 30 of the leaf springs being in engagement with seats 308 provided adjacent the column guides.

With construction such as shown herein, an economical truck is provided, and one making for ease in riding qualities. The elliptic springs, 35 working together with the coil springs, prevent oscillation or bouncing of the truck and car by virtue of the friction between the leaves of the elliptic springs. Thus increased spring capacity is obtained without requiring additional sets of 40 springs, as would be the case if elliptic springs and coil springs supported the loads independently. The elliptic springs produce a dampening effect by rebuking the harmonic action of the coil springs. The movable bolster, in the combination set forth, permits the car to roll or oscillate transversely without a great tendency to force the wheel over the rail, as would be the case were the bolster rigidly fixed to the truck.

It is to be understood that I do not wish to 50 be limited by the exact embodiments of the device shown, which are merely by way of illustration and not limitation, as various and other forms of the device will of course be apparent to those skilled in the art without departing from 55 the spirit of the invention or the scope of the claims.

I claim:

1. In a truck, the combination of a side frame having tension and compression members and 50 column guides therebetween forming an opening therein, a bolster extending into said opening, a spring mounting resiliently supporting said bolster on said side frame, said spring mounting including a coil spring and a semi-elliptic spring 55 supporting said bolster in parallel, said coil spring being disposed in said opening, and vertically fixed spring seats on said side frame spaced apart a distance greater than the length of said opening for supporting said semi-elliptic spring.

2. In a truck, the combination of a side frame having tension and compression members and column guides therebetween forming an opening 70 therein, a bolster extending into said opening, a spring mounting resiliently supporting said bolster on said side frame, the springs of said mount-

ing being of different character, one of said springs being semi-elliptic, and vertically fixed spring seats on said side frame for supporting said semi-elliptic spring, said spring seats being spaced apart a distance greater than the length 5 of said opening, the other of said springs being disposed on said side frame between said spaced seats.

3. In a truck, the combination of a side frame having tension and compression members and 10 column guides therebetween forming an opening therein, a bolster extending into said opening, a spring mounting resiliently supporting said bolster on said side frame, said mounting movably supporting said bolster with respect to said frame, the springs of said mounting being of the coil and semi-elliptic type disposed to support 15 said bolster in parallel, said coil springs being disposed in said opening, and vertically fixed spring seats on said side frame spaced apart a distance 20 greater than the length of said opening for supporting said semi-elliptic springs.

4. In a truck, the combination of a side frame having tension and compression members and 25 column guides therebetween forming an opening therein, a bolster extending into said opening, a spring mounting resiliently supporting said bolster on said side frame, said mounting movably supporting said bolster with respect to said frame, the springs of said mounting being of the coil and semi-elliptic type, the coil springs being disposed on each side of the semi-elliptic springs and in said opening, and spaced spring 30 seats on said side frame for supporting said semi-elliptic spring, said spaced seats being so constructed and arranged that movement of the 35 bolster causes equal deflection of said coil and semi-elliptic springs.

5. In a truck, the combination of a side frame having tension and compression members and 40 column guides therebetween forming an opening therein, a bolster extending into said opening and cooperating with said column guides, coil 45 springs supporting said bolster on said side frame, and a longitudinally disposed leaf spring supporting said bolster in parallel with said coil springs on fixed seats on said side frame adjacent said column guides, whereby movement of said bolster causes equal deflection of said coil and leaf springs.

6. In a truck, the combination of a side frame having tension and compression members and 50 columns therebetween forming an opening therein, said columns having column guides, a bolster extending into said opening and cooperating with 55 said column guides, coil springs supporting said bolster on said side frame, and a longitudinally disposed leaf spring supporting said bolster on said side frame in said tension member, said leaf spring being so constructed and arranged that the length of said spring is greater than the width of said opening, said leaf spring having a 60 spring band, and means on said bolster for transmitting load from said bolster to said leaf spring through said band.

7. In a side frame the combination of tension and compression members merging adjacent the ends thereof and provided with journal boxes rigidly mounted thereon, integral connecting columns connecting said tension and compression members and forming a window therewith, said side frame having a coil spring seat and spaced leaf spring seats, said last named seats being spaced apart a distance substantially greater than the width of said window.

8. In a truck the combination of spaced side frames having tension and compression members and column guides therebetween forming an opening in each of said frames, a spring plank disposed between said side frames and extending into said openings and seated on said tension members, a load carrying member extending into said openings, sets of coil and semi-elliptic leaf springs supporting said load carrying member on said tension members in said openings, each leaf and each coil spring of each set being adapted to deflect substantially the same amount upon movement of said load carrying member, one of said sets of springs being seated on means separate from said spring plank.
9. In a railway car truck, spaced side frames having central bolster openings, central spring seats at the bottom of said openings, auxiliary spring seats between said central seats and the ends of the frames, groups of springs supported on the central spring seats, laminated springs supported on and spanning said auxiliary seats, and a transverse bolster having its ends guided in said central openings and being supported on said groups of springs and additionally supported on said laminated springs.
10. In a railway car truck, spaced side frames having central bolster openings, central load supporting seats at the bottom of said openings, auxiliary load supporting seats between said central seats and the ends of the frames, groups of resilient means supported on said central seats, flexible supporting means spanning said auxiliary seats, and a transverse bolster having its ends guided in said central openings and being supported on said groups of resilient means and said flexible supporting means.
11. In a railway car truck, spaced side frames having bolster openings therein, a transverse bolster with its ends guided in said openings, each of said side frames having a central spring supporting portion, coil springs on said spring supporting portion for supporting the ends of the bolster, inclined tension members extending from said spring supporting portion, and semi-elliptic springs supporting the bolster ends and having their ends seated on said inclined tension members and intermediate the ends of said tension members.
12. In a railway car truck, spaced side frames having bolster openings therein, a transverse bolster with its ends guided in said openings, each of said side frames having a central spring supporting portion, spaced coil springs on said spring supporting portion for supporting the ends of the bolster, tension members extending from said spring supporting portion, and semi-elliptic springs engaging the bolster ends and having their ends seated on said tension members, said semi-elliptic springs being interposed between said coil springs and having their ends supported at points on said tension members beyond said central spring supporting portion to thereby distribute the load over a material length of said side frame in order to prevent concentration of the load at the central spring supporting portion.
13. In a railway car truck, spaced side frames having bolster openings therein, and a transverse bolster having its ends guided in said openings, each of said side frames having a central spring supporting portion, tension members extending from said spring supporting portion, bolster columns rising upwardly from said spring supporting portion and tension members, said tension members and bolster columns each having spaced side walls integral with the other, semi-elliptic springs extending longitudinally of said side frames between the side walls thereof and having their ends supported by said tension members at a distance from said spring supporting portion, said semi-elliptic springs being in load supporting engagement with said bolster, and coil springs supported by said central spring supporting portion on opposite sides of said semi-elliptic springs, said coil springs being disposed to engage said bolster.
14. In a railway car truck, spaced side frames having bolster openings therein, and a transverse bolster having its ends guided in said openings, each of said side frames having a central spring supporting portion, inclined tension members extending from said spring supporting portion, bolster columns rising upwardly from said spring supporting portion and tension members, said tension members and bolster columns each having spaced side walls integral with the other, said side walls of said tension members having transverse spring seats, semi-elliptic springs extending longitudinally of said side frames intermediate the side walls of said bolster columns and tension members and having their ends supported by said seats, and coil springs supported by said central spring supporting portion on opposite sides of said semi-elliptic springs, all of said springs being disposed to support said bolster.
15. In a car truck, the combination of a side frame having tension and compression members, spaced struts integrally connecting said tension and compression members, vertically rigid spaced seats provided on said side frame below said spaced struts, said tension member being provided with a spring supporting portion intermediate said spaced seats, a load carrying member supported on said side frame by a leaf spring supported on said spaced seats and coil springs supported on said spring supporting portion.
16. In a car truck, the combination of a side frame having tension and compression members, spaced struts integrally connecting said tension and compression members, vertically rigid spaced seats provided on said side frame below said spaced struts, said tension member being provided with a spring supporting portion intermediate said spaced seats, a load carrying member supported on said side frame by a longitudinally disposed semi-elliptic spring supported on said spaced seats and coil springs supported on said spring supporting portion.
17. In a car truck, the combination of a side frame having tension and compression members, spaced struts integrally connecting said tension and compression members, vertically rigid spaced seats provided on said side frame below said spaced struts, said tension member being provided with a spring supporting portion intermediate said spaced seats and adjacent the transverse center line of said truck, and a load carrying member supported on said side frame by a leaf spring supported on said spaced seats and coil springs supported on said spring supporting portion.
18. In a side frame, the combination of journal boxes, spaced seats for a leaf spring, coil spring seats between said spaced seats, and a strut member having an interrupted portion for accommodating the leaf spring disposed between said spaced seats.
19. In a car truck, the combination of a side frame having tension and compression members,

spaced struts integrally connecting said tension and compression members and forming windows, vertically rigid spaced seats provided on said tension member adjacent said spaced struts, said 5 tension member being provided with a spring supporting portion intermediate said spaced seats, a load carrying member supported on said side frame by a leaf spring supported on said spaced seats and coil springs supported on said spring 10 supporting portion and disposed on each side of said leaf spring.

20. In a car truck, the combination of a side frame having tension and compression members and spaced connecting struts disposed there- 15 between, spaced vertically rigid seats on said side frame, a leaf spring supported on said spaced seats, a load carrying member supported on said leaf spring, and a spring of different character from said leaf spring for supporting said load 20 carrying member in parallel with said leaf spring, said last named spring being seated on said side frame below the support of said leaf spring on said side frame.

21. In a car truck, the combination of a side frame having tension and compression members and spaced connecting struts disposed there- 25 between and forming a window therewith, spaced vertically rigid seats on said side frame, a leaf spring of greater length than the width of said 30 window supported on said spaced seats, a load carrying member supported on said leaf spring, and a spring of different character from said leaf spring for supporting said load carrying member in parallel with said leaf spring, one of 35 said springs being seated on said side frame below the support of the other of said springs on said side frame.

22. In a car truck, the combination of a side frame having tension and compression members and spaced connecting struts disposed there- 40 between, spaced vertically rigid seats on said side frame, a leaf spring supported on said spaced seats, a load carrying member supported on said leaf spring, and a spring of different character 45 from said leaf spring for supporting said load carrying member in parallel with said leaf spring, said last named spring being seated on said side frame below the support of said leaf spring on said side frame.

23. In a car truck, the combination of a side frame having tension and compression members and spaced connecting struts disposed there- 50 between, spaced vertically rigid seats on said side frame, a longitudinally disposed leaf spring supported on said spaced seats, a load carrying member supported on said leaf spring, and a spring of different character from said leaf spring for supporting said load carrying member in parallel 55 with said leaf spring, said last named spring being seated on said side frame below the support of said leaf spring on said side frame.

24. In a car truck, the combination of a side frame having tension and compression members and spaced connecting struts disposed there- 60 between, a spring supported on said side frame, a load carrying member supported on said spring, and a spring of different character from said first named spring for supporting said load carrying member in parallel with said first named 65 spring, said last named spring being seated on said side frame below the support of said first named spring on said side frame, one of said springs being a leaf spring disposed longitudinally of said truck, each of said springs being

adapted to deflect the same amount upon movement of said load carrying member.

25. In a car truck, the combination of a side frame having tension and compression members and spaced connecting struts disposed there- 5 between and forming a window therewith, a spring supported on said side frame, a load carrying member supported on said spring, and a spring of different character from said first named spring for supporting said load carrying member in parallel with said first named spring, said last named spring being seated on said side frame below the support of said first named spring on said side frame, one of said springs being a longitudinally disposed leaf spring of greater 10 length than the width of said window.

26. In a car truck, the combination of a side frame including tension and compression mem- 15 bers merging adjacent the ends thereof and pro- 20 vided with journal boxes, spaced integral struts connecting said tension and compression mem- 25 bers, a load carrying member having an end thereof disposed between said struts, the end of said load carrying member being recessed to receive a portion of a semi-elliptic spring dis- 30 posed to be seated on said side frame longitudinally thereof on spaced vertically fixed seats, and resilient means disposed on said side frame adjacent said spring for supporting said load carrying member in parallel with said semi- 35 elliptic spring.

27. In a car truck, the combination of a side frame including tension and compression mem- 40 bers merging adjacent the ends thereof and pro- 45 vided with journal boxes, spaced integral struts connecting said tension and compression mem- 50 bers, a load carrying member having an end thereof disposed between said struts, the end of said load carrying member being recessed to receive a portion of resilient means disposed to 55 be seated on said side frame longitudinally thereof on spaced vertically fixed seats, and re- 60 sili- 65 lent means of different kind than said first named resilient means disposed on said side frame adjacent said first named resilient means whereby said last named resilient means sup- 70 ports said load carrying member in parallel with said first named resilient means.

28. In a truck, the combination of a side frame having tension and compression members 50 and column guides therebetween forming an opening therein, a bolster extending into said opening, a spring mounting resiliently supporting said bolster on said side frame, said spring mounting including a coil spring and a semi- 55 elliptic spring supporting said bolster in parallel, said semi-elliptic spring being disposed in the plane of said side frame, said coil spring being disposed in said opening, and spaced vertically fixed spring seats on said side frame 60 spaced apart a distance greater than the length of said opening for supporting said semi-elliptic spring.

29. In a truck, the combination of a side frame having tension and compression members 65 and column guides therebetween forming an opening therein, a bolster extending into said opening, a spring mounting resiliently supporting said bolster on said side frame, the springs of said mounting being of different character, 70 one of said springs being semi-elliptic, said semi-elliptic spring being disposed in the plane of said side frame, and spaced vertically fixed spring seats on said side frame for supporting said semi-elliptic spring, said spring seats being 75

spaced apart a distance greater than the length of said opening, the other of said springs being disposed on said side frame between said spaced seats.

- 5 30. In a truck, the combination of a side frame having tension and compression members and column guides therebetween forming an opening therein, a bolster extending into said opening, a spring mounting resiliently supporting said bolster on said side frame, said mounting movably supporting said bolster with respect to said frame, the springs of said mounting being of the coil and semi-elliptic type disposed to support said bolster in parallel, said semi-elliptic spring 10 being disposed in the plane of said side frame, said coil springs being disposed in said opening, and spaced vertically fixed spring seats on said side frame spaced apart a distance greater than the length of said opening for supporting said semi-elliptic springs.
- 15 31. In a railway vehicle, spaced side frames having bolster openings therein and a transverse bolster having its ends guided in said openings, each of said side frames having a central spring supporting portion, tension members extending from said spring supporting portion, columns with bolster guiding surfaces rising upwardly from said spring supporting portion and tension members, said tension members and bolster columns each having spaced side walls 20 integral with the other, each of said tension members having means providing spring seats fixed with respect thereto, semi-elliptic springs extending longitudinally of said side frames intermediate the side walls of said bolster columns 25 and tension members, to beyond said guiding surfaces, and supported by said seats, and coil springs supported by said central spring supporting portion on opposite sides of the vertical center line of said semi-elliptic springs, all of 30 said springs being disposed to support said bolster.

distance from said spring supporting portion by leaf spring seats fixed with respect to the respective side frames and interposed between the semi-elliptic springs and tension member, said semi-elliptic springs being in load supporting engagement with said bolster, and coil springs supported by said central spring supporting portion on opposite sides of the vertical center line of said semi-elliptic springs, said coil springs being disposed to engage said bolster.

32. In a railway vehicle, spaced side frames having bolster openings therein and a transverse bolster having its ends guided in said openings, each of said side frames having a central spring supporting portion, inclined tension members extending from said spring supporting portion, columns with bolster guiding surfaces rising upwardly from said spring supporting portion and tension members, said tension members and bolster columns each having spaced side walls 20 integral with the other, each of said tension members having means providing spring seats fixed with respect thereto, semi-elliptic springs extending longitudinally of said side frames 25 and tension members, to beyond said guiding surfaces, and supported by said seats, and coil springs supported by said central spring supporting portion on opposite sides of the vertical center line of said semi-elliptic springs, all of 30 said springs being disposed to support said bolster.

FRED E. BACHMAN.
